(57) **CLAIM**

The ornamental design for a bottle, as shown and described.

DESCRIPTION

FIG. 1 is a front elevational view of a bottle showing my new design, the back elevational view being a mirror image of the front elevational view;

FIG. 2 is a left side elevational view thereof, the right side elevational view being a mirror image of the left side elevational view;

FIG. 3 is a top plan view thereof;

FIG. 4 is a bottom plan view thereof; and,

FIG. 5 is an overhead perspective view thereof.

The even broken lines in the figures represent unclaimed subject matter and form no part of the claimed design. The uneven broken lines in FIGS. 3 and 5 represent a boundary line that forms no part of the claimed design.
